UNITED STATES PATENT OFFICE.

WILLIAM W. LASKER, OF BROOKLYN, NEW YORK, ASSIGNEE, BY MESNE ASSIGNMENTS, TO REMINGTON RAND INC., OF NEW YORK, N. Y., A CORPORATION OF DELAWARE.

CONTACT UNIT FOR TYPEWRITER-KEY PUNCHES.

Application filed March 3, 1925. Serial No. 12,981.

This invention relates to the punching of cards for use in adding, tabulating, accounting or other machines wherein the mechanism is caused to function in a predetermined manner by an arrangement of perforations in the card, and more particularly relates to a mechanism whereby the operation of a typewriter in the compilation of statistics or other data simultaneously perforates 10 a card in a manner representing the item or data transcribed by the typewriter.

Some of the objects of the present invention are to provide an attachment for a typewriter whereby operation of certain of the 15 keys of such typewriter simultaneously causes the actuation of certain corresponding card perforating devices; to provide a complete unitary contact mechanism for selectively controlling a card perforating 20 punching mechanism; to provide a selective contact mechanism for a punching mechanism which is operated by the actuation of the keys of a typewriter; to provide a contact unit arranged to be quickly attached to 25 a standard typewriter in operative relation to the keys thereof whereby the operation of the typewriter automatically controls the set-up and operation of a key punch for perforating data cards; and to provide other 30 improvements as will hereinafter appear.

In the accompanying drawings, Fig. 1 represents a front elevation of a contact mechanism embodying one form of the present invention attached in operative position to a typewriter; Fig. 2 represents a section on line 2-2 of Fig. 1; and Fig. 3 is a diagram of two of the control circuits of which the others are a reduplication.

Referring to the drawings, one form of 40 the present invention is shown as applied to the electrical control of a punch or card perforating mechanism 10 by the mechanical operation of a typewriter 11 through the movement of its keys 12 as the typewriter is operated. While but a fragmentary portion of the punching mechanism 10 is shown, because that per se forms no part of the present invention, it will be readily understood by those skilled in the art, and also 50 that it is of the type wherein a preliminary set-up of the punches is made and thereafter an actuating mechanism causes simultaneous

operation of such punches as have been selected. In the type of punching mechanism here selected by way of example the punches 55 are respectively controlled by solenoids 13, which are arranged to be selectively energized by circuits 14. Since the selective mechanism for these circuits 14 is remote from the punching mechanism in the sense 60 that it is under the control of an instrumentality distinct from the punching mechanism the several conductors of these circuits are preferably made up in the form of a cable 15 which extends from the solenoids 65 13 and source of current 16 to a casing or box 17 wherein the aforesaid conductors are distributed as will be explained.

For the purpose of closing the respective 70 circuits 14, the casing 17 has mounted therein a plurality of pairs of contacts 20 and contactors 21, one contact and one contactor being in each circuit so that the bringing together of any such pair causes the circuit of that pair to be closed and the corresponding solenoid energized. As the construction 75 and arrangement of these contacts and contactors are all alike, repetition of description will be avoided by selecting one pair as an illustration of all. Thus a contact 20 is carried by a rigid conducting arm 22 which is supported in depending position from a composite strip 23 of insulating material fixed to the casing 17. This strip 23 also preferably forms a support for a flexible conducting arm 24 carrying the contactor 21, which is disposed in juxtaposed relation to, but normally spaced from, the contact 20. The arm 22 is connected by a conductor in the cable 15 which forms a branch of the circuit 80 controlling the solenoid 13 corresponding to the number or position of the selected contact in the series, while the contactor 21 is bonded to a terminal rod or wire 25 which is electrically connected by a wire 26 to a 85 common return conductor in the cable 15 for all of the circuits.

In order to cause the arm 24 to bring its contactor 21 against the contact 20 to close a circuit, an offset or projection 27 is formed 90 on the arm 24 to extend into the path of movement of a lug or offset 28 carried by a key bar or key stem 30. This key bar or key stem 30 is mounted for free sliding move-

ment in the direction of its length by passing it through the top 31 and bottom 32 of the casing 17, its projecting upper end having a head 33 fixed thereon to be used as a 5 key and constituting an abutment for a coil spring 34, the opposite end of which seats upon the top 31. The lower projecting end of the bar 30 carries a rigid bifurcated finger 35 normally seating against the under face 10 of a key 12 of the typewriter keyboard, this key, of course, corresponding to the circuit which the associated contact and contactor are to close by the pressing down of that key. Normally the spring 34 holds the bar 30 in 15 its up position, and returns it to that position after the typewriter key has been released following its operation. Thus when the key 12 is pressed down in the ordinary typewriting operation it carries with it the bar 30 and since the stroke is long enough to bring 20 the offset 28 past the offset 27, the movement causes the flexible arm 24 to move towards the rigid arm 22 and bring its contactor 21 against the contact 20 to thus close the circuit including solenoid 13.

It is to be remembered that the foregoing description relates to one unit or one circuit control while the complete device is made up of a plurality of such units, each comprising 30 a circuit including a solenoid 13, a contact 20 and contactor 21, and a bar 30 with its adjuncts for causing it to be actuated by a separate typewriter key. There are as many circuits as there are perforating punches to 35 be set up, and the complete assembly of units is mounted in the casing 17 with the respective actuating bars 30 projecting for operation by the keys 12. As here shown there are ten units, one to be controlled by each 40 of the number keys of the typewriter, and consequently there are ten selectively controlled pins for setting up the punches for the perforating operation. As heretofore explained, all of the circuits have a common 45 source of current and a common return conductor, whereby the wiring is materially simplified.

For controlling the movement of the perforating machine carriage, the casing 17 is 50 provided with extra keys, here shown as a carriage space key 40, a carriage return key 41, a carriage skip key 42, and a card trip key 43, which respectively control the closing of circuits for controlling the operation of 55 the perforating machine. Such a machine and its control is shown in Patent No. 1,305,557, dated June 3, 1919. It will thus be evident when, for example, the key for numeral "5" on the typewriter is operated that there 60 will be a simultaneous closing of the circuit which energizes the solenoid 13 for controlling the setting pin 44 which sets up punch "5." As soon as this is set up the pin carriage automatically moves to the next space so that the next typewriter key operated will

set up a punch in the next adjacent row and this continues until all the data to be recorded on one card by perforation is set up. Then the card trip key 43 is pressed down and all of the set-up punches perform the 70 perforating operation. Following this the carriage return key 41 is pressed down so that the pin carriage returns to starting position to make a new set-up for the next card. The pin carriage space and skip are 75 controlled by the pressing down of either the key 40 or the key 42.

Having thus described my invention, I claim:

1. In a card perforating system, the combination of a typewriter, a punch mechanism, electrical means for actuating said punch mechanism, a plurality of electrical circuits for selectively controlling said means, a casing arranged to be connected to 80 said typewriter, contact mechanism in said casing for respectively closing said circuits, means in said casing for governing the action of said contact mechanism, and means extending through said casing and operatively connecting said governing means and certain of the typewriter keys for selective control of said contact mechanism by movement of said certain of the typewriter keys. 95

2. In a card perforating system, the combination of a typewriter, a punch mechanism, electrical means for actuating said punch mechanism to accomplish plural functions, a plurality of electrical circuits for selectively controlling said means, a casing adapted for attachment on the typewriter, respective control means for said circuits disposed in said casing, means carried by said casing and associated with certain of the typewriter keys to operate certain of said circuit control means whereby to accomplish a function of the punch mechanism, and manually operated means in said casing for selective operation of others of said circuit control means whereby to accomplish another function of the punch mechanism. 100

3. In a card perforating system, the combination of a typewriter; a punch mechanism; electrical means for actuating said punch mechanism; a plurality of electrical circuits for selectively controlling said means; a circuit control box comprising a casing adapted for mounting on the typewriter, circuit closers for said circuits disposed in said casing, and operating members for said circuit closers movable in and through the casing; and key engaging extensions on each of said operating members. 115

4. In combination with a typewriter 120 equipped with the usual set of typewriter keys, a second set of keys, punches, means for selecting said punches by depression of said second set of keys, and connections between corresponding keys of said sets of 130

keys for operating the second set of keys by an operation of the first set and permitting an operation of the second set independently of an operation of the first set.

5. In a machine of the class described, the combination of the usual set of typewriter keys, a second set of keys, and a mechanical connection between corresponding keys of

the two sets of keys for depressing keys of the second set by depression of keys of the first set and for permitting independent depression of the keys of the second set.

Signed at Philadelphia, county of Philadelphia, State of Pennsylvania, this 19th day of February, 1925.

WILLIAM W. LASKER.
